F. F. BESSINGER,

PISTON RING,

APPLICATION FILED JAN. 26, 1920.

1,371,066.

Patented Mar. 8, 1921.

UNITED STATES PATENT OFFICE.

FRANK F. BESSINGER, OF WELLINGTON, OHIO.

PISTON-RING.

1,371,066.

Specification of Letters Patent. Patented Mar. 8, 1921.

Application filed January 26, 1920. Serial No. 354,281.

To all whom it may concern:

Be it known that I, FRANK F. BESSINGER, residing at Wellington, in the county of Lorain, State of Ohio, have invented certain new and useful Improvements in Piston-Rings, of which the following is a full, clear, and exact description.

The primary object of this invention is to produce a simple and efficient piston ring 10 which may be cheaply manufactured.

A further object of the invention is to produce a pair of piston rings which are exact duplicates and when fitted together may be easily applied to the ordinary piston to form 15 a packing ring which will prevent loss of compression and leakage of gas and yet will have considerable elasticity to conform to the bore of the cylinder.

Another object of the invention is to make 20 a pair of piston rings which will not pull apart axially but will be locked together in use, thus preventing the accumulation of carbon, dirt, etc., between the rings which would tend to permanently separate them 25 and make them leak gas.

In the accompanying drawings,

Figure 1 is a plan view of one of the rings with the eccentric rib up.

Fig. 2 is a plan view of one of the rings 30 with the rib down.

Figs. 3 and 4 are sectional views taken on lines 3-3 and 4-4, Fig. 1.

Fig. 5 is plan view of a pair of rings assembled and contracted as in use on a piston 35 in a cylinder, the piston and cylinder not showing.

Fig. 6 is a sectional view on line 6-6, Fig. 5.

The piston ring consists of two split rings 40 A and B, which are of identical construction. Only one, therefore, will be described in detail.

The ring has a face 1 which is plane (see Fig. 2) and a face 2 from which arises the 45 upstanding eccentric rib 3. (See Fig. 1). The outside periphery of the ring is a true circle to conform to the engine cylinder to which it is applied. The inner periphery of the face 1 is a true circle eccentric to the 50 outside periphery. A small tongue 4 projects inwardly a uniform distance around the inner periphery of the ring and corresponds in curvature to the inner periphery of the face 1. The inner periphery for one- 55 half the circumference of the face 2 of the ring is formed by the above mentioned small

tongue 4. Around the other half of the inner periphery of face 2, projects the upstanding eccentric rib 3.

The outer periphery of the rib 3 is formed 60 with the same radius as the inner periphery of the corresponding face of the other ring at the split in order that they may fit closely together (as seen in Fig. 5). Obviously the center for the curve of the outer periphery of the rib 3 is slightly above the true center of the ring. The inner periphery of the upstanding rib 3 is formed on a radius from the true center of the circle. Thus the rib 3 is eccentric. The ring as a whole is also 70 eccentric.

From this construction it will be seen that the ends of the upstanding rib 3 are of substantial thickness and are partly inside and partly overlying the face 2 of the ring, although the rib extends substantially half-way around the circumference of the ring. This makes a stronger and tighter construction than when these ends are formed so that they become very thin and do not extend as 80 far around the ring.

As the inner periphery of the rib 3 is eccentric, the overhanging part gradually decreases until at the thickest portion of the eccentric rib its inner periphery nearly coincides with that of the tongue 4. At the base of the upstanding rib 3 and around the outer periphery of such rib is formed a small groove 5 of the appropriate size to receive the tongue 4 of the other ring. 90

The ring gradually increases in width from the thinnest portion (which is split at 6 to permit it to be applied to a piston) until the opposing portion 7 is preferably substantially double the thickness. The eccentric rib 3 increases in thickness from its ends to a point equidistant from them. 95

To form a complete piston ring two of the above eccentric rings with their ribs are opposed and fitted together so that the eccentric rib of one engages the inner periphery of the other at the split and the groove 5 receives the tongue 4 of the other, thus locking the rings together to prevent their separation when in use. It is quite common for 100 two-part rings to have dirt or carbon collect and grow in the crack between the rings, thus separating them and causing leakage of gas. This of course cannot occur with 105 my rings which are held together so that 110 foreign material cannot cause them to separate. As the outer curve of the eccentric

rib has the same radius as the inner periphery of the opposing ring they fit very tightly.

The split part of each ring may have a 5 butt joint, a bevel or step split or it may have a lap joint, though the latter is not necessary with my ring construction as the engagement of the eccentric rib of one ring with the split part of the other prevents 10 leakage of gas transversely.

By this construction it will be seen that the disadvantage of having the thin ends of the ordinary eccentric ring which often permits leakage of gas is entirely overcome, 15 for when the pair of rings are assembled they are of substantially uniform width and thickness. Yet the advantage of the more uniform expansion of the eccentric ring is obtained.

20 What I claim as my invention is:

1. A piston ring packing consisting of a pair of split rings, each ring having a grooved rib adjacent the inner periphery and extending around substantially half the 25 circumference and each having a tongue adjacent the inner periphery at the split, the curvatures of said tongue and grooved rib being substantially the same.

2. A piston ring packing consisting of a 30 pair of split rings of substantially identical construction, each having an eccentric rib of substantial thickness throughout, said rib lying adjacent the inner periphery and extending substantially half way around the 35 same and having a grooved portion, and a tongue adjacent the inner periphery of the ring at the split.

3. A piston ring packing consisting of a pair of split rings each having an eccentric

rib with a groove to interlock with the 40 split portion of the other ring, such portion having a tongue formed thereon.

4. A piston ring packing consisting of a pair of eccentric split rings each having an eccentric rib with a groove, and a tongue in 45 the other ring to fit such groove.

5. A piston ring packing consisting of a pair of split rings of substantially identical construction, each having a rib with a groove to interlock with the split portion of 50 the other ring, such portion having a tongue formed thereon, and the rib having a substantial thickness throughout its length.

6. A piston ring packing consisting of a pair of split rings of substantially identical 55 construction, each having a rib with a groove to interlock with the split portion of the other ring, such portion having a tongue formed thereon, and the rib extending substantially half way around the ring. 60

7. A piston ring packing consisting of a pair of split rings of substantially identical construction, each having an eccentric rib extending substantially half way around the ring and having a substantial thickness 65 throughout its length, said rib partially over-hanging the inside of the ring.

8. A piston ring packing consisting of a pair of eccentric split rings, each having an eccentric rib extending substantially half 70 way around the ring and having a substantial thickness throughout its length, said rib partially over-hanging the inside of the ring.

In testimony whereof I hereunto affix my 75 signature.

FRANK F. BESSINGER.
